(57) **CLAIM**

The ornamental design for an active seat with storage, as shown and described.

DESCRIPTION

FIG. 1 is a top perspective view of an active seat with storage according to the present invention;

FIG. 2 is a bottom perspective view of the active seat with storage of FIG. 1;

FIG. 3 is a first side elevational view of the active seat with storage of FIG. 1;

FIG. 4 is a second side elevational view of the active seat with storage of FIG. 1;

FIG. 5 is a front elevational view of the active seat with storage of FIG. 1;

FIG. 6 is a rear elevational view of the active seat with storage of FIG. 1;

FIG. 7 is a top plan view of the active seat with storage of FIG. 1; and,

FIG. 8 is a bottom plan view of the active seat with storage of FIG. 1.

The broken lines in the drawings illustrate portions of the active seat with storage that form no part of the claim.
